PENCIL

Perry Feuer, Roslyn, N.Y., assignor to Creative Creations, Inc., New York, N.Y.

Filed Apr. 21, 1971, Ser. No. 136,293

Term of patent 14 years

Int. Cl. D19—06

U.S. Cl. D74—24

FIG. 1 is a front view of a pencil showing my new design;

FIG. 2 is a right side view; the left side being a mirror image thereof; and

FIG. 3 is a rear view thereof.

I claim:

The ornamental design for a pencil, as shown and described.
